CARD DISPLAY RECEPTACLE FOR AUTOMOBILES

Filed Dec. 29, 1923

INVENTOR.
H. H. DEDMON.
BY Joseph B. Gardner
ATTORNEY

UNITED STATES PATENT OFFICE.

HANSON H. DEDMON, OF BERKELEY, CALIFORNIA.

CARD-DISPLAY RECEPTACLE FOR AUTOMOBILES.

Application filed December 29, 1923. Serial No. 633,370.

My invention relates to a receptacle removably mounted on an automobile and adapted for displaying a card such as a license certificate.

6 An object of the invention is to provide a device of the character described which is adapted to be removably secured to the steering post of an automobile.

Another object of the invention is to provide 10 a card display receptacle which may be attached to an automobile without the use of screws, bolts or nails.

The invention possesses other objects and 15 features of advantage, some of which, with the foregoing, will be set forth in the following description of the preferred form of my invention which is illustrated in the drawings accompanying and forming part of the specification. It is to be understood that

20 I do not limit myself to the showing made by the said drawings and description, as I may adopt variations of the preferred form within the scope of my invention as set forth in the claims.

25 Referring to said drawings:

Figure 1 is a side view showing the device of my invention secured to the steering post of an automobile.

Figure 2 is a plan view, slightly in perspective, showing the device extended.

Figure 3 is a sectional view taken on the line 3—3 in Figure 2.

Figure 4 is a perspective view of another embodiment of my invention.

35 Figure 5 is a sectional view of the embodiment shown in Figure 4, the plane of the section being indicated by the line 5—5 of the latter figure.

The almost universal requirement that 40 automobile license cards be carried and displayed in the driver's compartment of the vehicle necessitates the provision of a suitable card receptacle carried therein. Such receptacle must be substantially moisture and 45 dirt proof and should be so mounted that it may not be readily opened or removed by an unauthorized person. The types of receptacles heretofore used have been adapted to be fastened to the dash or instrument 50 board by means of screws or bolts and have usually been lacking in attractiveness. However, in the device of my invention I provide a flexible receptacle of pleasing appearance which is adapted to be positioned and held 55 in flexed position encircling the steering post of the automobile. In this manner, the li-

cence is plainly displayed, forming holes in the dash or instrument board is avoided, and the receptacle may be placed in or removed from the display position with a minimum 60 of effort.

As illustrated in Figures 1 to 3, the receptacle of my invention comprises a casing 6 having a back wall 7 preferably of rectangular shape and of a size slightly in excess of the usual automobile certificate of registration. Arranged on the forward face of said wall at oppositely disposed edges thereof are members 8 and 9 which with the wall define pockets 10 in which oppositely disposed edges 12 of a transparent front wall 13 are adapted to be positioned.

The certificate 14 is adapted to be inserted 65 between the front and rear walls of the casing, and its corresponding edges are likewise adapted to be inserted in the pockets.

Both the walls 7 and 13 are formed of a flexible material so that the casing may be readily flexed about the steering post or other cylindrical object fixed to automobiles. The oppositely disposed edge portions 15 and 16 of the rear wall are provided with extensions 17 and 18, the former of which is preferably permanently fixed in folded position over the face of said wall to define a pocket 19 in which the edge 21 of the front wall is adapted to be disposed. The other extension 18 while normally adapted to be disposed in folded position over the back wall, may be unfolded and extended to permit the 90 registration card to be readily inserted between the casing walls or removed therefrom.

Means are provided for securely holding the casing in flexed position around the 95 steering post. As here shown, flexible straps 22 and 23 overlie and are secured to the extensions 17 and 18. These straps are preferably provided with buckles 24 at one end and perforations 26 adjacent the other end. 100 With this type of fastening means, the necessary adjustment is provided for adapting the attachments of the casing to steering columns of various sizes.

It will be noted that when the casing is 105 flexed about the steering post, the edge portions 8 and 9 are arranged in juxtaposition; means are therefore provided for permitting these portions to be locked together to prevent the surreptitious removal of the casing from the steering post. As here shown, 110 said edge portions are provided with rings

27 securely fastened thereto. An ordinary padlock may then be used to connect the rings.

I have found that by making the front 5 wall of celluloid, and the remainder of the structure of leather, that the necessary flexure of the casing is provided.

In Figures 4 and 5, is illustrated a slightly modified form of the invention. As here 10 shown, the receptacle comprises a metallic resilient band 31 of segmental form and adapted to be placed around the steering post. The edges of the band are formed with inwardly extending flanges which overlie 15 the outer face of the band and define therewith pockets for the reception of the edges of the license certificate and a transparent cover 32 therefor. The adjacent edge portions 33 and 34 are adapted to be connected 20 by a segment 36 which is hinged to the edge 33 and connected by bolts 37 to the edge 34.

I claim:

1. A card display receptacle for automobiles comprising a compartment having a flexible back wall, edge members arranged on said back wall forming pockets along adjacent edges thereof, a flexible transparent front wall having its edge portions disposed in said pockets, an edge member fixed to said back wall and adapted to be folded over an edge of said front wall, and means for securing the receptacle in flexed position around the steering post of said automobile.
2. A card display receptacle for automobiles comprising a compartment having a flexible back wall, members arranged on said back wall and overlying oppositely disposed edges thereof to form pockets, a flexible transparent front wall having its corresponding edges positioned in said pockets, and means for securing the receptacle in flexed position about the steering post of the

automobile comprising an edge member hinged to said back member and adapted to 45 be folded over an edge of said front member not arranged in said pockets.

3. A card display receptacle of the character described, comprising a compartment having a flexible back wall and a flexible 50 transparent front wall between which the card may be interposed, and adjustable means for removably securing the receptacle in flexed position around a cylinder member and comprising a flexible strap secured to 55 the receptacle at its edge and arranged to completely encircle the receptacle when flexed about said member.

4. A card display receptacle for an automobile comprising a compartment having 60 a flexible back wall, edge members arranged on said back wall and cooperating therewith to define pockets along the edges thereof, a flexible transparent front wall having edge portions disposed in certain of 65 said pockets, and a flexible member at one of said edges adapted to close the open end of the compartment and for securing the receptacle in flexed position around a cylindrical member of an automobile.

5. A card display receptacle for automobiles, comprising a compartment for a card having a flexible back wall and a flexible transparent front wall, an adjustable means for removably securing the receptacle in flexed position around a cylindrical member comprising flexible straps carried by and passing over the outside edges of the receptacle, one of said straps attached to a member which closes the open end of said compartment.

In testimony whereof, I have hereunto set my hand at Oakland, California, this 13th day of December, 1923.

HANSON H. DEDMON.
